UNITED STATES PATENT OFFICE.

DALTON K. WILSON, OF WATERLOO, IOWA.

CULTIVATOR.

1,350,050.

Specification of Letters Patent. Patented Aug. 17, 1920.

Application filed June 30, 1919. Serial No. 307,608.

To all whom it may concern:

Be it known that I, DALTON K. WILSON, a citizen of the United States of America, and a resident of Waterloo, Blackhawk county, 5 Iowa, have invented certain new and useful Improvements in Cultivators, of which the following is a specification.

My invention relates to improvements in cultivators. The object of my improvements 10 is to furnish a self-propelled device supplied with independently operable gangs of soil-working implements; having means for controlling the direction of travel of the device, and also having means for unitedly manu- 15 ally controlling said gangs of implements and steering the device, the last-mentioned means being also movably associated with said gangs to permit said means to be used in changing the direction of travel of the de- 20 vice without acting upon the gangs.

This object I have accomplished by the means which are hereinafter described and claimed, and which are illustrated in the accompanying drawings, in which Figure 1 is 25 a side elevation of my improved cultivator; Fig. 2 is a top plan view thereof, with part of the frame broken away, and Fig. 3 is a rear elevation thereof.

Similar numerals of reference denote cor- 30 responding parts throughout the several views.

My improved cultivator is preferably of a self-propelled type, but the character of my improvements is such that they may be used 35 in the same manner in cultivators or similar machinery, which may not be self-propelled.

The numeral 24 denotes a horizontally dis- 40 posed hollow rectangular frame having fixed hangers 50 provided with outwardly extend- 45 ing stub axles on which are rotatably mount- ed the traction-wheels 49. Sprocket-wheels 50 of the spur-tooth type 51 are concentrically mounted on said traction-wheels by clamp- 55 ing members 52 and carry sprocket-chains 53 which are carried over and driven by 45 sprocket-pinions 54 on a rotatable shaft 55 whose end parts are mounted in raised bear- 50 ings 73 on the side-bars of said frame. The 55 numeral 57 denotes a sprocket-wheel fixed 50 on a differential-gear casing 64 and which 55 houses differential gearing of the internal-gear type (not shown), such as is shown in my previous Patent No. 1,051,475, January 28, 1913. Said transmission device is loose 55 on said shaft but may be engaged therewith

to rotate with the shaft by the following means:

65 is a sleeve grooved annularly to receive a shifting-fork 66 on a bent arm 67, said sleeve being slidably non-rotatably mounted 60 on said shaft and having a clutch-face, not shown, to engage a mating clutch-face in said housing connected therewith. The arm 67 is one of the members of a bell-crank lever which is pivoted at its angle on a stud 68 on 65 the rear cross-bar of the frame. The outer end of the member 69 of said lever has an eye to receive a hooked end of a rod 70 whose rear end has a looped handle 71. Manipula- 70 tion of the bell crank lever by said handled rod 70 shifts the clutch-sleeve 65 into or out of mesh with the clutch-member, not shown, within the housing 64. A prime mover 61 of the double opposed cylinder type, is mounted on the front part of said frame, 75 and a sprocket pinion 59 is mounted on the end of its power-shaft 60 to carry a sprocket-chain 58 which is also carried by the sprocket-wheel 57.

I have provided means for changing the 80 direction of travel of said wheeled-frame 24. The numeral 17 denotes a flat horizontal rock-bar positioned immediately under said frame to extend rearwardly thereof, and having its front end pivoted at 16 to a cross- 85 bar 72 of said frame. The front end of this rock-bar is formed with the forwardly ex- 90 tending rack-segment 15. The middle part of said rock-bar is mounted and supported in a hanger 18 depending from the frame to swing transversely therein, and the rear part of the rock-bar is offset downwardly and provided with upwardly directed spaced lugs 19 and 20 between which the middle part of a bowed axle 47 is secured by means of a 95 bolt 21, and said bolt has a rearwardly ex- 100 tending stem 22, with a terminal looped han- 105 dle 23 for a purpose to be described.

Small carrying-wheels 48 are mounted on the depressed ends of the bowed axle 47, ro- 100 tatably. The numeral 14 denotes a rack- 105 segment which intermeshes with the rack- segment 15 and is pivoted at 12 to a cross- bar 13 of said frame. Said rack-segment 14 has a forwardly extending medial projection 105 62, and a helical tension spring 63 is con- 110 nected between said projection and the front cross-bar of said frame, and acts to normally retain said rack-segments and rock-bar in the medial longitudinal line of said frame. 115

Arms 11 extend integrally and transversely oppositely from the rack-segment 14. The numeral 7 denotes a pair of spaced longitudinally disposed controller-bars positioned 5 immediately below the frame 24 to extend rearwardly therefrom, and are located on opposite sides of the rock-bar 17. The front ends of said controller-bars are movably coupled to the ends of the rack-segment arms 10 11 by the pivoted connections 8—9, to permit free swinging movements of the controller-bars. The rear extremities of the controller-bars have clutch-disks 6 radially grooved or dentated to mate with similar clutch-disks 15 5 on the front ends of arms 2, and said clutch-disks are adjustably secured together by bolts 3 and wing-nuts 4. The rear ends of the adjustable arms 2 are supplied with the looped handles 1.

20 A bar 26 is fixedly secured along the under face of the front cross-bar of the frame 24 by bolts 25, and has at each end depending hangers 32 with outwardly turned portions to which are pivotally secured on vertical pivots to swing horizontally hanger-parts 33 having integral flanged members 27 supplied with a vertical row of bolt-holes 31. A pair of longitudinally disposed bars 30 have front terminal forks 29 mounted to swing vertically on the plate 27 by means of bolts 28. These pivoted connections render the forward ends of the gang-bars freely movable relative to the hangers 32. The rear ends of the gang-bars 30 are 35 swingingly connected to the rear part of the main frame 24 by the following means:

The numeral 43 denotes tubular standards whose upper ends are traversed by eye-bolts 44. Looped-shaped links 45 are linked 40 to said eye-bolts and the outturned extremities are pivoted in staples 46 fixed on said frame. Each standard 43 is fixedly connected by means of side-plates 41 to aligned standard members 40 below and spaced 45 therefrom, the lower ends of the latter being connected to the rear ends of the gang-bars 30 by movable joints 39. Within the interspace of the side-plates 41 are mounted a pair of vertically-spaced anti-friction rollers 42 and the controller-bars 7 are passed slidably between said anti-friction rollers. On the rear ends of the gang-bars 30 are fixed hangers 34 having sleeves 35 in which are mounted the tubular supports 36, the 55 latter orificed to receive the shanks 37 of shovels 38.

As shown in said Fig. 1, the gang-bars 30 are independently controlled, and the frame 24, with its carrying-wheels 49, move 60 to change the direction of travel by manual actuation of the controller-bars or devices 2—7 alone. To change the direction of travel of the device, the operator shifts the controller-bars 7 longitudinally oppositely, said bars sliding between the side-

plates 41 of the standards 40—43 without acting to shift the gang-bars laterally. These movements of the controller-bars rock said rack-segments 14 and 15 appropriately to rock the rock-bar 17 in a desired direction, and as the rear end of the rock-bar is connected to the middle of the bowed axle 47, the latter, with its carrying-wheels 48 serve as fulcrumming-means so that the frame 24 and its carrying-wheels 49, are rocked 75 relative to said rock-bar on the pivot or king-bolt 16 to change their direction of travel.

Either controller-device 2—7 may be used independently of the other by moving it 80 transversely to and fro to swing its connected gang-bar 30 transversely, or lifted or depressed to raise and lower the gang-bar with its soil-working tools 38. This operation of either or both of the gang-bars, by 85 means of said controller devices, may be effected while the controller-devices are being shifted slidably longitudinally to change the direction of travel of the device.

The handle 23 may be used in lifting the 90 wheels 48 off the ground in swinging the device a half turn in reversing the direction of travel.

Various modifications may be effected in the elements of the device and their arrangements, and yet be covered by the scope of the invention.

Having described my invention, what I claim as new and desire to secure by Letters Patent, is:

1. In combination, a frame, means of transportation including steerable elements on which said frame is mounted for relative movements of said steerable elements, gangs of implements movably supported on said frame, and loosely connected mechanisms operatively associated with said frame, said means of transportation, the steerable elements thereof, and with said gangs of implements, movable separably to steer said device or vertically or laterally to shift said gangs of implements, or together to perform both said operations simultaneously.

2. In combination, a frame, steerable means of transportation therefor, implement-supporting elements movably connected to said frame, and slidably connected elements movably associated with the steerable parts of the device and with said implement-supporting elements, operable to actuate them either together or independently of each other, and to shift the implement-supporting elements vertically or laterally during either of said actuations.

3. In combination, a frame mounted for 125 transportation, hangers for implements movably supported on said frame independently, and controlling-means slidably movably associated with said hangers and movably connected to said frame and adapted 130

for coördinated or independent actuations for steering the device and moving the hangers vertically or laterally either together or independently.

5 4. In combination, a steerable frame mounted for transportation, tool-carrying hangers suspended from said frame, and manually operable means operatively connected to said frame to change its direction of travel and loosely disconnectedly secured to said hangers to shift them when said means is moved in certain directions, and to leave the hangers unaffected when said means is moved in certain other directions.

10 5. In combination, a frame, means of transportation therefor, a wheeled fulcruming device, a rigid bar fixedly connected to said fulcruming device and pivotally connected to said frame, oppositely movable manually-controlled elements, and mechanism connected between said elements and said bar operable to rock said bar oppositely to change the direction of travel of said means of transportation relative to said fulcruming device.

15 6. In combination, means of transportation, a frame mounted thereon, a fulcruming traveling device pivotally connected to said frame, said traveling device including a rock-bar pivoted to the frame and having a terminal rack-segment, another rack-segment pivoted on said frame and in mesh with the first mentioned rack-segment, and means movably connected to said second mentioned rack-segment to rock it, together with the first mentioned rack-segment and said frame, to change the direction of travel of the frame and its means of transportation.

20 7. In combination, means of transportation, a frame mounted thereon, a fulcruming traveling device pivotally connected to said frame, said traveling device including a rock-bar pivoted to the frame and having a terminal rack-segment, another rack-segment pivoted on said frame and in mesh with the first mentioned rack-segment, a yieldable resilient connection between the second-mentioned rack-segment and the frame, and means movably connected to said second mentioned rack-segment to rock it, together with the first mentioned rack-segment and said frame, to change the direction of travel of the frame and its means of transportation, hangers independently movably mounted on said frame, said last mentioned

means being so movably associated with said hangers as to be adapted for occasionally shifting the hangers without rocking the frame or for occasionally rocking the frame without shifting the hangers.

25 8. In combination, means of transportation, a frame mounted thereon, trailer carrying-wheels, a sub-frame mounted on the latter and connected pivotally to said frame, hangers for implements suspended movably and independently from said frame, and independent adjustable manually-controlled devices operatively connected to said sub-frame, and independently movably connected to said hangers.

30 9. In combination, means of transportation, a main frame mounted thereon, a sub-frame pivotally connected to said main frame and having carrying-wheels, a pair of controller-bars operatively connected to said sub-frame, implement-carrying hangers movably suspended on said main frame, and operative connections between said hangers respectively and the adjacent ones of the controller-bars permitting independent actuations of the hangers by the controller-bars, and also permitting actuations of the main-frame without actuating the said hangers.

35 10. In a translatable soil-tilling device containing direction-changing mechanism and relatively movable implements, manually-operable controllers, and an operating connection between the controllers and said mechanism and implements adapted to permit the controllers when shifted to and from longitudinally to actuate the direction-changing mechanism without shifting the implements, or when simultaneously shifted transversely to shift both simultaneously.

40 11. In a translatable soil-tilling device containing direction-changing mechanism and a movable tilling tool, manually-operable controllers movably connected to both by a slidale loose connection permitting independently shifting of either selectively.

45 12. In a translatable device, containing direction-changing mechanism and also a movable tool, manually-operable controllers movably connected to both by a loose connection permitting operation of said mechanism only by longitudinal movements of the controllers.

Signed at Waterloo, Iowa, this 27th day of June, 1919.

DALTON K. WILSON.
